OPENABLE COVER FOR AN ELECTRIC CIRCUIT CONTROLLER CASING

Harry J. Collins, Jr., Bayside, Wis., assignor to Cutler-Hammer, Inc., Milwaukee, Wis., a corporation of Delaware

Application May 26, 1959, Serial No. 56,084

Term of patent 14 years

(Cl. D26—13)

Figure 1 is a perspective view of an openable cover for electric circuit controller casing, showing my new design;

Fig. 2 is a partial sectional view on line 2—2 of Fig. 1 to an enlarged scale;

Fig. 3 is a top plan view of the cover of Fig. 1; and

Fig. 4 is a bottom end view of the cover of Fig. 1.

I claim:

The ornamental design for an openable cover for an electric circuit controller casing, substantially as shown.
